JERRY H. WONSER, OF PORT ANGELES, WASHINGTON.

MAGAZINE LUBRICATOR.

Application filed May 2, 1925. Serial No. 27,400.

This invention relates to magazine lubricators and has as one of its objects to provide a lubricator that is adaptable to many uses.

5 Another object of the invention is to provide a lubricator that by its construction is sufficiently compact to form a practical hub cap for automobiles.

A further object of the invention is to provide 10 a lubricator having a relatively large storage capacity.

A further object of the invention is to provide 15 a lubricator having an automatic discharge, under pressure, of a predetermined portion of its contents.

A further object of the invention is to provide 20 a lubricator having means whereby an intermittent discharge may be provided, and whereby the discharge may be suspended for an indefinite period.

With these and other objects in view reference is now had to the accompanying drawings in which

Fig. 1 is a sectional elevation of the lubricator showing the parts in the position of total discharge;

Fig. 2 is a partial sectional view of the lubricator showing the parts in a position for filling;

30 Fig. 3 is a partial sectional elevation of a modified form of the lubricator showing its adaptability as a hub cap;

Fig. 4 is a plan view of the head of the magazine;

35 Fig. 5 is a fragment of the head showing in plan the centrally positioned orifice;

Fig. 6 is an enlarged view of a fragment of the head showing the operation of the latch; and

40 Fig. 7 is a fragment of the device showing a modified form of studs and head.

Having reference to the drawings like numerals refer to like parts throughout the several views and the numeral 1 refers to 45 the lubricator.

While the application of the lubricator is well understood its application as a hub cap is essentially important and is plainly shown in Fig. 3 where 2 represents a fragment of 50 a hub of an automobile wheel.

The lubricator consists of a cup 3 which from its relatively large capacity, and from the facts that a relatively small portion of its contents is discharged at one time and 55 that the discharge is at optional periods, will be termed a magazine, and as such the

cup will be referred to in the following pages.

Let it here be understood that the terms "automatic" and "intermittent" as herein used will be construed as meaning that the discharge is automatic as it is yieldingly expelled, and that it is intermittent as a portion of its contents is to be discharged at a time and at optional periods.

The magazine 3 is preferably of cylindrical form and its base 4 terminates in a threaded portion 5 for engagement with the parts to be lubricated.

The magazine is provided with an inlet 6 positioned well up on its side wall 7, for a purpose to be explained, and is also provided with the usual discharge orifice 8.

Closing the end of the magazine is a shaped head 9 that is formed with a raised portion 10, shaped as shown in Fig. 1 or with the legs 10^a as shown in Fig. 7, for a purpose that will be presently explained, and centrally positioned in the raised portion is an orifice 11 that is preferably shaped as a Greek cross with four equal arms and angles.

A cap 12 is slidably mounted on the magazine in a manner to expose the inlet 6 when the cap is withdrawn its limit, and thus provides an opening through which to fill the magazine, and by the movement of the cap on the magazine to close the inlet during the operation of the lubricator.

The cap is free to rotate on the magazine 90 and has rigidly attached to its central part, on its interior, a regulating stem 13 that is rotatable with the cap, the latter comprising preferably a round rod provided with studs 14 which extend radially from the 95 stem.

The studs are positioned in staggered relation to each other so as to bring each succeeding pair at right angles to the next pair that they may pass through the centrally positioned orifice 11 in the head 9.

Attached to the regulating stem is a plunger 15 which is constructed of a washer 16, a leather 17, and a second washer 18, all laying adjacent to each other in the usual manner of plunger construction.

These three elements are secured to the stem by means of a nut 19 and may be mounted thereon in a manner to enable the stem to be rotated without affecting the 110 plunger.

The plunger is shaped by providing an

upturned edge 20 on the washer 18, as shown in Fig. 1, and the body of the plunger may be further shaped (see Fig. 3) by drawing the edges downward from the 5 plane of the body and forming the three elements as one, as and for the purpose explained below.

Shaping of the plunger is required for two purposes, i. e. that of retaining a 10 spring 21 in a generally central position in the magazine, and to conform to the general contour of the base 4 when the base is of special design as when the device is used as a hub cap in which case the base is lowered away from the discharge orifice to provide for capacity.

Where the lubricator is designed as a hub cap it is obviously necessary to prevent too great an extension of the lubricator hence 20 the base is lowered as above mentioned, and thus to expel the contents from the lowered base the plunger must be shaped to fill the recess therein.

The spring 21 is designed of a conical 25 shape and is interposed between the plunger 15 and the head 9 to force the plunger downward thereby to expel the contents of the magazine.

To conserve space the spring is further 30 designed so that it will lay flat when compressed and thus require a space merely the thickness of the wire of which the spring is composed.

Now to prevent any lateral motion of the 35 spring the above mentioned upturned edge 20 will retain the base of the spring and the raised portion 10 will form means to retain the top of the spring. Legs 10^a may also be utilized for this purpose if desired.

40 By this arrangement the spring is maintained in its proper position and is thus prevented from moving laterally against the stem to intercept the studs and thereby interfere with the operation of the device.

45 It is now evident that with the cap 12 withdrawn the plunger will be moved in the same direction as the cap and that this action will uncover the inlet 6 and position the parts so that the magazine may be filled. 50 With the filling accomplished the spring which is now compressed, will tend to force a discharge of the contents.

To provide now for controlling the action of the plunger by restricting its compressive movement, and also to provide for a free return movement, a latch 22 is provided which comprises preferably spring members 23 that are secured to the head in any suitable manner, as at 24.

60 The springs are set in the recess 22^a to bring them even with the surface of the head 9 so that the head presents a smooth surface on which the studs may be freely turned.

65 The springs may be curved on one end 25

to supply a seat for the studs 14 and are arranged with the curved portion of each spring resting opposite to each other and over opposite arms of the cross shaped orifice.

70 By this means two of the studs will be intercepted as the stem is moved downward by the action of the spring and to release the studs from the springs the cap will be rotated one quarter turn which will bring the intercepted studs free from the springs and in register with the exposed arms of the orifice through which they may now pass.

The stem 13 will now move downward and this movement will continue until the next 80 succeeding studs are intercepted by the latch.

In withdrawing the cap to renew the charge in the magazine the studs will pass freely through the respective arms of the orifice and the latch will permit of this free 85 movement by its yielding qualities, in the manner and as shown in Fig. 6.

It will thus be seen that the action of the 90 device is intermittent, discharge taking place only after each quarter rotation of the stem, and gradually thereafter, until a certain amount has been discharged depending upon the distance apart of the studs.

The studs may also be oblong in section, 95 as shown in Fig. 7, and positioned with their long side vertical thus forming a guide to prevent the rod turning in its upward movement, and in this case the studs will be spaced apart the thickness of the head 9.

In use the device is attached to the journal to be lubricated, the cap is then withdrawn until the orifice is uncovered and the magazine is then filled in the usual manner.

100 The cap is now rotated until the first pair of studs are free of the latch when the spring 21 will force the plunger against the contents. A specific amount of the lubricant will now be expelled to enter the bearing, and as the lubricant in the bearing becomes exhausted the cap will again be rotated a quarter turn and lubrication will be resumed.

105 The magazine being finally emptied the cap will be withdrawn as before, the magazine again filled, and the operation resumed.

110 Having thus described my invention, I claim—

115 1. In a magazine lubricator, a magazine provided with an inlet and a discharge orifice, a head adapted to close one end of said magazine and provided with a raised portion, and containing a centrally positioned orifice in said raised portion, a cap slidably mounted on said magazine in a manner to slidably cover said inlet, a regulating stem rigidly attached to said cap and provided 120 with studs extending laterally therefrom, and positioned in staggered relation to each other, a plunger attached to said stem and slidably mounted in said magazine, a yielding means designed to conform to the shape 125 130

of said head when compressed, and interposed between said plunger and said head, said raised portion forming means to prevent a lateral motion of said yielding means, 5 and a latch attached to said head to operably register with said studs.

2. In a magazine lubricator, in combination with a magazine having an inlet and a discharge orifice, a head in said magazine, 10 and a cap slidably mounted on said magazine in a manner to slidably cover said inlet, of a regulating stem rigidly attached to said cap and provided with studs positioned in staggered relation to each other, a yieldingly 15 operable plunger attached to said stem, and a latch attached to said head in operable contiguity with said studs to provide means

to cause an automatic intermittent discharge from said magazine.

3. In a magazine lubricator, the combination with a magazine having a base, of a cap slidably and rotatably mounted on said magazine, a regulating stem rigidly attached to said cap for rotation therewith and provided with studs positioned in staggered relation to each other, a yieldingly operable plunger attached to said stem, and a latching means positioned in operable contiguity with said studs and arranged to release said studs successively by the rotation of said 30 cap.

In testimony whereof I affix my signature.

JERRY H. WONSER.
